ENVELOPE

Elijah G. Vallier, Wauwatosa, Wis., assignor to
 Western States Envelope Company, Milwaukee,
 Wis., a corporation of Wisconsin

Application January 11, 1933. Serial No. 651,065

9 Claims. (Cl. 229—71)

This invention relates to improvements in envelopes.

In view of the fact that many States and counties issue automobile drivers' licenses and registration certificates, there is considerable demand for an inexpensive window envelope which is especially adapted to receive a relatively small card of the type used for this purpose. As a general rule, these cards are so small that if they are mailed in an envelope of the same size, it is objectionable to the postal authorities. Furthermore, the cards usually have the name and address near the top or in such a position that if an ordinary envelope is used, the window must be near the top edge if provision is to be made for proper registration with the name and address on the card. Inasmuch as the postal laws require a clear space of at least 1½ inches at the top for cancellation purposes, the designing of a suitable envelope has presented a considerable problem.

Heretofore, various envelopes have been devised for handling cards of the type referred to. These envelopes have been constructed with interior adhesive areas or lines to define a space of smaller size than the envelope for receiving the card and for properly positioning the latter relative to the window. Necessarily, in the manufacture of this envelope, great care must be used in the application of the adhesive to insure proper registration of the card with the window, and the cost of manufacture is therefore relatively high.

It is one of the objects of the present invention to provide an envelope for the purpose described which is designed to hold a card of smaller size with the address in proper registration with an intermediately located window, the envelope being so formed that the necessity of employing carefully located interior adhesive areas is eliminated.

A more specific object of the invention is to provide an envelope wherein an extension flap is employed adjacent an edge, said flap being adhesively secured to the interior of the envelope, and the side flaps being so formed as to be co-operable with said extension flap in causing proper positioning of the card.

A further object of the invention is to provide an envelope of the class described which can be manufactured with a minimum of material.

A still further object of the invention is to provide an envelope of the class described which can be so formed as to serve a dual purpose—

that of holding a license plate, catalog or the like in addition to the card.

A further object of the invention is to provide an envelope which is suitable for use in mailing any type of relatively small card, where- 60 in the same problem is present as in the mailing of drivers' licenses, registration certificates, or the like.

A further object of the invention is to provide an envelope which is simple in construction, neat in appearance, and well adapted for the purpose described.

In the accompanying drawing in which the same reference numerals designate the same parts in all of the views: 70

Fig. 1 is a plan view showing an envelope blank used in carrying out the present invention;

Fig. 2 is a plan view of a card of the type suitable for use in the improved envelope; 75

Fig. 3 is a plan view of the rear of the envelope before final sealing, showing the card in position;

Fig. 4 is a plan view showing the front of the envelope with the edges reversed in position 80 from Fig. 3;

Fig. 5 is a transverse sectional view taken on line 5—5 of Fig. 4; and

Fig. 6 is a plan view showing the rear of a modified form of envelope adapted for the simultaneous mailing in separated compartments of a card and a larger enclosure such as a license plate. 85

Referring more particularly to the drawing, the blank is cut out in the shape shown in Fig. 1 to provide a main section 8 having a foldable sealing flap 9, a foldable extension flap 10, and foldable side flaps 11. The blank is also formed with a cut-out 12 forming a window, and the said window may or may not be provided with 95 a transparent covering 13.

The sealing flap 9 has its outer edge coated with a layer of suitable adhesive as at 14, in the usual manner. In addition, the extension flap 10 is also formed near its outer edge with 100 adhesive material 15. The blanks are assembled into envelope form by first folding the side flaps 11 inwardly and then by folding the extension flap 10 upwardly over the lower portions of the side flaps in the manner 105 shown in Fig. 3, the extension flap being caused to adhere to the main section 8 of the envelope between the side flaps, as at 16, and also to the lower portions of the side flaps, as at 17. Thus, the upper edge 18 of the exten- 110

sion flap 10 (referring to the position in Fig. 3) is secured to the main body 8 the entire distance between the side flaps 11 to form a positive stop. In view of the fact that most certificates of registration or drivers' licenses are a part of a long form and are separated therefrom before mailing to the applicant, the name and address frequently appear on the card in such a position as to render it difficult to procure proper registration of the name and address with a window in an envelope, and still maintain said window the proper distance from the upper edge of the envelope as required by law. Referring to the driver's license 19 illustrated in Fig. 2, which is typical of the type of card for which the envelope has been designed, it will be seen that the address appears relatively near the upper edge of the card. If this card were inserted in an envelope of substantially the same size and a window were formed in the envelope to register with the name and address, the window would be too close to the upper edge of the envelope. If the card were reversed in position, of course, the name and address would appear upside down, and if it were attempted to utilize the opposite edge of the envelope as the top in mailing, the window would still be too close to said edge. With the present envelope, the card shown in Fig. 2 is inserted upside down in the envelope, while the latter is in the position shown in Fig. 3. The envelope is of such size that the space above the edge 18 of the extension flap 10 is substantially the same size as the card. The card is therefore inserted below the side flaps 11 until the bottom edge abuts the edge 18 of the extension flap. Due to the fact that this edge 18 is secured to the main section 8 of the envelope, the card cannot be moved any lower. The window 12 in the envelope is so positioned that when the card is in the position shown in Fig. 3, that the name and address will be in registration with said window, the said name and address, however, being upside down with relation to the sealing flap 9. Next, the gummed edge 14 of the sealing flap 9 is moistened and said flap is lowered in the usual manner and caused to adhere to the outer side of the extension flap 10. The edges of the envelope are then reversed in position as shown in Fig. 4 to bring the name and address right side up, and thus what was formerly the lower edge of the envelope is the upper edge in transit. Due to the additional material formed by the extension flap 10 and the material in the body 55 thereof, ample space is provided above the window for the stamp and for cancellation purposes, as clearly shown in Fig. 4.

From the above, it may readily be seen that an envelope of larger size than the card which it is adapted to receive has been devised, wherein means is provided for positively insuring proper registration of the name and address on the card with a properly located window in the envelope. It will further be seen that this is accomplished without utilizing carefully located adhesive areas on the interior of the envelope as has been proposed in prior patents. With applicant's arrangement, once the blank is properly cut, it is merely necessary to cause the extension flap 10 to adhere over the side flaps in the manner shown in Fig. 3, and it will readily be seen that it is simple to apply the adhesive to the extension flap 10, as the adhesive merely has to be extended along the edge of said flap, and it is not necessary to

apply carefully located adhesive areas to the interior of the main section 8 or to intermediate portions of the flaps requiring careful gauging.

In the form of the invention illustrated in Fig. 6, the same principles are utilized, with the exception of the fact that the extension flap 10' and the portion of the main section therebelow are much greater in length. Also, the side flaps 11 are lengthened proportionately. In this form of the invention, the extension flap 10' is adhesively secured along the side edges as at 20, as well as on the end edge 21. Prior to the securing of the extension flap 10' in place, however, a license plate, catalog or the like is inserted below the flap 10' so that when said flap is secured in the position shown in Fig. 6, it forms a sealed compartment for the enclosure, separating the latter from the enclosure for the card 19. The sealing flap 9 for the card enclosure is then sealed in the same manner as in the main form of the invention, after the card has been inserted. Thus, an envelope has been provided which is suitable for the mailing under a single cover of a card requiring one class of postage and of an insert requiring another class of postage.

It is obvious that the particular style of the envelope of Fig. 1 and Fig. 6 may be varied in accordance with the particular shape of the articles to be mailed, and that various other changes, modifications and adaptations may be devised without departing from the spirit of the invention, and all of such changes are contemplated as may come within the scope of the claims.

What I claim is:

1. An envelope comprising a main section having a window therein, side flaps having portions spaced from one another to expose the inner side of the main section of the envelope, means extending transversely of the envelope and having its upper edge portion secured to the exposed inner side of the main section between the side flaps to serve as a stop and thereby cause proper registration of an insert with the envelope window, and means for closing the envelope.

2. An envelope comprising a main section having a window therein, side flaps spaced from one another to expose the inner side of the main section of the envelope, an upwardly folded extension flap having its upper edge secured to the exposed inner side of the main section and to the lower portions of the side flaps to serve as a stop and thereby cause proper registration of an insert with the envelope window, and means for closing the envelope.

3. An envelope comprising a main section having a window therein, a pair of oppositely disposed side flaps, a lower flap secured to the lower portions of the side flaps and to the inner side of the main section to form a stop and thereby cause proper registration of an insert with the envelope window, and means for closing the envelope.

4. An envelope comprising a main section having a window therein, a pair of relatively narrow oppositely disposed side flaps, said side flaps being spaced apart a substantial distance, a lower flap secured to the lower portions of the side flaps and to the inner side of the main section between the side flaps to form a stop and thereby cause proper registration of an in-

- sert with the envelope window, and means for closing the envelope.
5. An envelope comprising a main section having a window therein, a pair of oppositely disposed side flaps, a lower flap secured over the lower portions of the side flaps and to the inner side of the main section to form a stop and thereby cause proper registration of an insert with the envelope window, and means for closing the envelope.
6. A window envelope for a card having an address near the upper edge thereof, comprising a main section having a window spaced substantially the same distance from the upper edge of the envelope as the address on a card to be inserted therein is spaced from the lower edge of said card, said window being spaced a substantial distance from the lower edge of the envelope, a pair of oppositely disposed side flaps, a lower flap having its free edge portion secured to the inner side of the main section between the side flaps to serve as a stop and thereby cause registration of the address on the card with the window when the card is inserted in inverted position, and means for sealing the envelope, the face of the envelope being read in reversed position in transit.
7. A double mailing envelope comprising a front section having a window therein, oppositely disposed side flaps folded on the inner side of said front portion, flap means foldable over an insert disposed between it and the front section, means for securing said flap means in position with its end edge below the window to serve as a stop and thereby cause proper registration of a card or the like with the envelope window and to define the lower edge of the card compartment, and means for closing said card compartment after the card has been inserted therein.
8. A double mailing envelope comprising a front section having a window therein, oppositely disposed side flaps folded on the inner side of said front section, a bottom flap foldable over an insert disposed between it and the front section, means for securing the sides of the bottom flap to the side flaps and for securing the end edge of the bottom flap to the inner side of the front section below the window to serve as a stop and thereby cause proper registration of a card or the like with the envelope window and to define the lower edge of the card compartment, and means for closing said card compartment after the card has been inserted therein.
9. A double mailing envelope comprising a front section having a window therein, oppositely disposed side flaps folded on the inner side of said front section, a bottom flap foldable over an insert disposed between it and the front section, means for securing the sides of the bottom flap to the side flaps and for securing the end edge of the bottom flap to the inner side of the front section below the window to serve as a stop and thereby cause proper registration of a card or the like with the envelope window and to define the lower edge of the card compartment, and means for closing said card compartment after the card has been inserted therein.
